LOOM TEMPLE

Francis J. Wilson, Riverside, R. I., assignor to
Mechanical Holding Corporation, a corporation
of Rhode Island

Application December 19, 1935, Serial No. 55,235

7 Claims. (Cl. 139—295)

This invention relates to a loom temple for holding woven fabric taut in a widewise direction in the loom; and has for one of its objects the provision of spring pressure in such a temple so arranged that there may be a balancing of the pressure between the end portions of the fabric gripping means for holding the same taut.

Another object of the invention is the provision of an arrangement by which uniform pressure across the engaging surfaces may be quickly acquired by an adjustment of the parts.

Another object of the invention is the provision of resilient means which may be easily and quickly adjusted to provide different desired pressures and either the same or different at opposite ends of the fabric engaging means.

Another object of the invention is an arrangement by which different pressures may be had for different fabrics, whereby a greater tension may be used for the heavier fabrics and a lighter tension for the lighter weight fabrics, without changing or interchanging any of the parts.

Another object of the invention is the provision of a means whereby the resilient pressure may be distributed against the member which contacts the upper surface of the cloth so that an even pressure along the surface may be obtained.

Another object of the invention is the provision of a spring which will act upon the member engaging the upper surface of the fabric from directly above this member so as to force the same downwardly from this superimposed position in substantially the direction it would travel by gravity.

With these and other objects in view, the invention consists of certain novel features of construction, as will be more fully described, and particularly pointed out in the appended claims.

In the accompanying drawings:

Fig. 1 is a top plan view of the cloth engaging portion of the temple with the securing portions shown fragmentally;

Fig. 2 is an end view of the cloth engaging portion of the temple with the holding means broken away;

Fig. 3 is a sectional view on substantially line 3—3 of Figure 1;

Fig. 4 is a sectional view on substantially line 4—4 of Figure 1;

Fig. 5 is a sectional view on substantially line 5—5 of Figure 1;

Fig. 6 is a perspective view of the hanger in which the upper roll is mounted;

Fig. 7 is a perspective view of the cap member

of the temple in which the hanger for the upper roll is guided and operates.

In the use of loom temples, it is frequently desirable that different pressures be had upon different fabrics, and also that a balanced pressure may be had so that the pressure will be uniform along the length of the presser member whereby a very firm grip may be established; and in order that these results may be accomplished, I have provided in a three-roll temple a hanger for supporting and mounting the upper roll, the same being guided towards the lower roll in a plane passing substantially between the rolls so that when the cloth is engaged it will be disposed in a sinuous path, and I have forced this carriage with the upper roll downwardly towards the lower roll by a pair of springs which are disposed in alignment with each other and also substantially in the plane of movement of the hanger so as to act directly from above the roll in forcing it downwardly towards the lower roll; and the following is a more detailed description of the present embodiment of this invention, illustrating the preferred means by which these advantageous results may be accomplished:

With reference to the drawings, 10 designates generally the base portion of the loom temple with an arm 11 extending to the bracket 12 for securing the temple in position.

This base is cast with recessed portions 15 and 16 for the reception of the rolls 17 and 18, which are mounted on the axles 19 and 20 extending into bearing supports 21 in one end wall 22 and similar bearing supports 23 in the end wall 24 at the other end. The axles threadingly engage one of said supports and are provided with a slotted end 21 for easy rotation. These rolls are thus mounted in spaced relation and provide spaced engaging surfaces for the traveling fabric or web 25 which passes through the temple. The surfaces of the rolls are grooved as at 26 in a known manner to better grip the fabric.

Mounted upon the base there is a cap member designated generally 30, and shown in perspective in Figure 7. This cap member has a tongue 31 to fit within a groove 32 in the base, while an opening 33 receives a bolt 34 which may be threaded into the base as at 35 to securely bind the cap member in superimposed relation over and spaced from the base. The opposite edges 36 and 37 of the cap are suitably rounded to engage the cloth and with the rolls will dispose the fabric web in a more or less sinuous path depending upon the thickness of the cloth.

Within the cap 30 there is mounted a hanger 55

40 which may move vertically in the guideways 41 and 42 between the opposite side walls 43 and 44 at one end and 45 and 46 at the other end. This hanger is provided with depending portions 47, 48 at its opposite ends, which provide bearings 49, 50 for a readily removable spindle 51 upon which the upper roll 52 is rotatably mounted. This spindle is threaded as at 53 which engages the thread in the opening 50 to hold the same in position. An enlarged slotted head 54 is provided at the end of the spindle for manipulation by a screw driver for interchanges of upper rolls. A bar 56 extends laterally across the hanger 40 and beyond the sides thereof to engage the abutments 57 on the opposite sides of the guide portion 41, while a bar 58 extends across the hanger at the opposite end for engaging the abutment 59 to support this end of the hanger against dropping from the cap.

The stops 56 and 58 are normally positioned well above their abutments 57 and 59 and the hanger is forced downwardly by two leaf springs 60 and 61 which are convex on their upper surface and concave on their lower surface providing spaced portions 62 and 63, 64 and 65 which engage at aligned points along the top surface of the hanger 40 so that when pressure is applied to the upper side of the spring at a point substantially half way between the points of contact, the springs will be forced downwardly against the hanger while in turn forcing the roll which it supports downwardly in a plane substantially between the rolls 17 and 18 so as to cause any fabric passing between these rolls to be firmly gripped thereby. In this manner, the pressure is located in substantially the direction or plane of the path of movement of the roll and is generally directly above it.

40 The threaded member 66 engages the upper portion of the springs 60 and 61 and has a slot in its head 67 so that it may be threaded downwardly through the threaded opening 68 in the bridging portions 69 and 70 of the cap to adjust the pressure upon the spring to the desired amount, which pressure having been obtained the hexagonal lock nut 72 is forced against the surface 73 of the bridge to hold this threaded member 66 in desired position for adjustment.

50 In order to prevent the springs from longitudinal movement or slipping from position, a screw 74 having a head 75 passes through an opening in the spring and into the pressure member 66 so as to hold the spring in desired position in the temple. This threaded screw 74 will not be caused to bind the spring against the bottom of the threaded member 66 but rather will permit rotation of the threaded member 66 without twisting the spring or turning the spring with it, by reason of a swivel arrangement.

By the construction provided, I may adjust the springs 60 and 61 so that they have the same amount of tension or they may be adjusted to have different amounts of tension, depending upon the objects desired to be accomplished. When set in their adjusted position the springs remain set at a fixed pressure until a change in the character of the fabric is made or a different pressure is desired. Thus, it is a simple matter to obtain the desired pressure adjustment after the temple is in position in the loom and after the fabric has been inserted through the rolls by a proper turning of the threaded members 66 so that it becomes unnecessary to take off the 75 cap for the preliminary insertion of the fabric

therein at the initial setting up of the loom and placing the fabric in the desired position to determine the relation of upper tensioning roll thereto.

The foregoing description is directed solely towards the construction illustrated, but I desire it to be understood that I reserve the privilege of resorting to all the mechanical changes to which the device is susceptible, the invention being defined and limited only by the terms of the appended claims.

10 I claim:

1. In a loom temple, a pair of spaced fabric engaging rolls, a hanger movable in a plane passing between said members, a roll rotatably mounted by said hanger, and a pair of elongated aligned arched springs each acting on said hanger solely at its end extremities to apply pressure thereto at a plurality of spaced points directly above the hanger roll and in the plane of its movement for moving said hanger in said plane generally towards said pair of rolls, and means for separately adjusting the tension on each of said springs by applying pressure thereto at a point substantially mid-way between the points of contact of its end extremities with the hanger for acquiring the desired tension on the ends of the hanger.

2. In a loom temple, a base having a pair of rotatable rolls thereon, a cap member fixed to said base and in a superimposed spaced relation thereto, said cap member having an elongated recess extending longitudinally inwardly from one end thereof for substantially the major length of the cap, a generally U-shaped hanger movably mounted in said recess for movement in a plane passing between said base rolls, a cloth-engaging roll rotatably supported on said hanger and adapted to be moved therewith in said plane, a plurality of resilient pressure members each of which is located in said plane and applying pressure to said hanger at a plurality of spaced points for moving said hanger and the upper roll carried thereby in said plane towards the base rolls, and individually adjustable members one connected to each of said resilient members to apply pressure to the upper side thereof at a point substantially mid-way between the points of contact of the latter with the hanger and in the plane of movement of said upper cloth-engaging roll.

3. In a loom temple, a base having a pair of rotatable rolls thereon, a cap member fixed to said base and in a super-imposed spaced relation thereto, said cap member having an elongated recess extending longitudinally inwardly from one end thereof for substantially the major length of the cap, a hanger movably mounted in said recess for movement in a plane passing between said base rolls, a cloth-engaging roll rotatably supported on said hanger and adapted to be moved therewith in said plane, a plurality of resilient arch-shaped pressure members each of which is located in said plane with its ends contacting said hanger for applying pressure to said hanger at a plurality of spaced points for moving said hanger and the upper roll carried thereby in said plane towards the base rolls, individually adjustable members connected to said pressure members to apply pressure to the upper side thereof at a point substantially mid-way between the points of contact of the latter with the hanger and in the plane of movement of said upper cloth-engaging roll, and swivel means for fixedly mounting said springs on said adjustable members for independent rotary adjusting movement thereof rela-

tive to said springs while maintaining the latter in said plane and in a normal pressure applying position on the hanger.

4. In a loom temple, a base having a longitudinal recessed portion and a laterally extending groove at one end, a pair of rolls rotatably mounted in said recess, a cap member in superimposed spaced relation above said base and fixed thereto, said cap member being provided with a tongue portion interfitting said groove, a hollow guide portion extending longitudinally of said cap member and having guide-ways at the opposite sides and ends thereof, a hanger movably mounted in said guide portion of said cap member for vertical movement in said guide-ways in a plane passing between said base rolls, a cloth-engaging roll rotatably mounted on said hanger for movement in said plane, a plurality of abutments on the opposite sides of said guide portion, a plurality of bars extending laterally across said hanger and engageable with said abutments in said cap to support and suspend said hanger therein to limit the extent of its descending movement, a plurality of leaf springs to apply pressure to said hanger at spaced aligned points along the top face thereof, individually adjustable pressure members to apply pressure to the upper side of said springs at a point substantially half-way between the points of contact of the latter with the hanger and in the plane of movement of the upper cloth-engaging roll and directly thereabove, and swivel means to mount and fix said springs on said adjustable pressure members from longitudinal movement yet permit rotation and adjustment of the latter without causing turning of said springs from a pressure applying position with respect to the hanger.

5. In a loom temple, a pair of spaced fabric engaging members, a hanger with a fabric engaging member mounted therein movable in a plane passing between said members, and resilient leaf springs convex on their upper surfaces and each arched to apply pressure solely by its end extremities to said hanger at a plurality of spaced points directly above the latter and in the plane

of its movement for moving said member in said plane and generally towards the pair of members.

6. In a loom temple, a base, spaced cloth engaging rolls rotatably mounted thereby, a cap supported by said base and having an extended portion overhanging the base and spaced therefrom, said overhanging portion being provided with a longitudinally extending opening therethrough, a carriage movably supported above said base for vertical movement in said opening in the cap, 10 said carriage being provided with guide surfaces at its sides and ends to slidably engage the adjacent wall surfaces of said opening and be guided thereby during vertical movement of the carriage, a cloth engaging roll rotatably mounted in said carriage and located partly between and above said spaced base rolls, and spring means for bodily moving the entire carriage with the roll carried thereby towards the rolls on said base, and means to prevent the carriage from 20 dropping through said opening.

7. In a loom temple, a base, spaced cloth engaging rolls rotatably mounted thereby, a cap supported by said base and having an extended portion overhanging the base and spaced therefrom, said overhanging portion being provided with a longitudinally extending opening therethrough, a carriage movably supported above said base for vertical movement in said opening in the cap, 25 said carriage being provided with guide surfaces at its sides and ends to slidably engage the adjacent wall surfaces of said opening and be guided thereby during vertical movement of the carriage, a cloth engaging roll rotatably mounted in said carriage and located partly between and above said spaced base rolls, and spring means for bodily moving the entire carriage with the roll carried thereby towards the rolls on said base, and a pair of bars located near the opposite end extremities of said carriage, each of said bars 30 extending laterally across the carriage and movable with the same to support said carriage in said cap against dropping therefrom after reaching the bottom limit of its descent.

FRANCIS J. WILSON.
